UNITED STATES PATENT OFFICE.

WILLIAM T. BRISTER, OF GUADALUPE COUNTY, TEXAS, ASSIGNOR OF
ONE-HALF TO FRITZ GALLE, OF GUADALUPE COUNTY, TEXAS.

HAME-HOOK.

No. 839,265.

Specification of Letters Patent.

Patented Dec. 25, 1906.

Application filed December 18, 1905. Serial No. 292,327.

To all whom it may concern:

Be it known that I, WILLIAM T. BRISTER, a citizen of the United States, residing in the county of Guadalupe and State of Texas, have invented a new and useful Hame-Hook, of which the following is a specification.

This invention relates to devices for coupling the traces to the hames in harness, and has for its object to improve the construction and increase the efficiency of devices of this character.

With these and other objects in view, which will appear as the nature of the invention is better understood, the invention consists in certain novel features of construction, as hereinafter fully described and claimed.

In the accompanying drawings, forming a part of this specification, and in which corresponding parts are denoted by like designating characters, is illustrated the preferred form of the embodiment of the invention capable of carrying the same into practical operation, it being understood that various changes in the form, proportion, and minor details of construction may be resorted to without departing from the principle or sacrificing any of the advantages of this invention within the scope of the appended claim.

Figure 1 is a perspective view of the device applied. Fig. 2 is a plan view of the improved device detached. Fig. 3 is a perspective view of a modified form of the device.

The improved device consists of a stock 10, formed from a metal plate or sheet and having an L-shaped transverse recess whereby a transverse hook 11 is formed at one end to receive the eye at the forward end of the trace and with a vertical hook 12 bent from the other end and at right angles to the hook 11 to engage the staple member 13 on the hame, a portion of one of which is represented at 14. Riveted or otherwise secured at 15 to the stock 10 is a spring 16, extending thence into the hook 12 and branching vertically in opposite directions, as at 17 18, and

thence extending laterally at 19 20 over and above the body of the stock.

The resiliency of the spring holds the arms 17 18 normally in yieldable engagement with the inner face of the hook 12 near its free end, 50 as shown. The lateral offsets 19 20 serve as guides to prevent accidental displacement of the spring.

A device thus constructed, it is obvious, may be readily snapped upon the staple 13 55 and be effectually retained thereon by the resiliency of the spring, which maintains the guide portions 19 20 presented edgewise to the member 13, so that all danger of displacement by the rearward movement of the 60 hames or forward movement of the stock 10 and its hooks is obviated.

The device is simple in construction, can be inexpensively manufactured, and operates effectually for the purposes described. 65

In Fig. 3 a modified construction is shown, consisting in forming the hook 12 with a transverse aperture 21, which may be required with some forms of hame connections.

Having thus described the invention, what 70 is claimed is—

In combination with a hame provided with a staple, a hame-hook comprising a plate having at its upper edge an L-shaped recess and at its forward end a return-bend adapted to 75 receive the hame-staple, a T-shaped spring attached to the outer side of said plate and having its head portion located under the return-bend of the plate, said head portion straddling the plate and having ends which 80 terminate flush with the under surface of the plate.

In testimony that I claim the foregoing as my own I have hereto affixed my signature in the presence of two witnesses.

WILLIAM T. BRISTER.
